C. H. GRINGS

FLY SWATTER

Filed Sept. 8, 1924

Inventor,
Casper Hugo Grings, by
G. Kennedy
Attorney.

Patented May 18, 1926.

Des. 70,166

UNITED STATES PATENT OFFICE.

CASPER HUGO GRINGS, OF WATERLOO, IOWA, ASSIGNOR TO WATERLOO SADDLERY COMPANY, OF WATERLOO, IOWA.

DESIGN FOR A FLY SWATTER.

Application filed September 8, 1924. Serial No. 10,698. Term of patent 14 years.

To all whom it may concern:

Be it known that I, CASPER HUGO GRINGS, citizen of the United States, residing at Waterloo, in the county of Black Hawk and State of Iowa, have invented a new, original, and ornamental Design for Fly Swatter, of which the following is a specification, reference being had to the accompanying drawing, forming part thereof.

The figure is a plan view of a fly swatter, showing my new design.

I claim:

The ornamental design for a fly swatter, as shown.

In testimony whereof I affix my signature.

CASPER HUGO GRINGS.
